UNITED STATES PATENT OFFICE.

GEORGE M. DEPEW, OF CANANDAIGUA, NEW YORK.

WATER-CLOSET.

No. 901,525.

Specification of Letters Patent.

Patented Oct. 20, 1908.

Application filed August 13, 1907. Serial No. 388,376.

To all whom it may concern:

Be it known that I, GEORGE M. DEPEW, a resident of Canandaigua, in the county of Ontario and State of New York, have invented certain new and useful Improvements in Water-Closets; and I do hereby declare the following to be a full, clear, and exact description of the invention, such as will enable others skilled in the art to which it pertains to make and use the same.

This invention relates to water closets, and has for its object to provide simple and efficient means for flushing water closets without the use of siphons or valves, and the invention consists in the construction herein-after described and particularly pointed out.

In the accompanying drawing which illustrates the invention and forms part of the specification,—Figure 1 is a vertical sectional view of the device; Fig. 2 is a partial sectional view at right angles to Fig. 1. Fig. 3 is a broken section showing guide ways in preferred form; Fig. 4 is a similar view of another form of guide ways; Fig. 5 is a partial view showing a modification of the connection between the weight and the receptacle.

Numeral 1 denotes a box or casing, and 2 a tilting water-receptacle or bucket suspended within the casing by means of a bail 3 and rod 4, the latter extending through the bucket and sliding in ways 5 fixed to the casing. These ways can be conveniently formed by soldering large wires 5^x to the wall of the bucket as indicated in Fig. 3, or by strips as in Fig. 4. The bucket bail 3 is in the preferred form suspended from the end of a bar or lever 6 having a pivotal support or fulcrum at 7 which may be a rod fixed to the walls of the casing.

5^x denotes a chain whereby the lever 6 is connected to a weight 7^x situated in a well or open-topped cylinder 8.

9 indicates a partition to exclude water from the weight and the interior of the guiding cylinder.

10 denotes a guide pulley for the chain and 11 a packing made of rubber, leather or other suitable material shaped to fit the walls of the well.

12 indicates a packing-retaining plate and 13 a screw for securing the plate and packing to the weight.

14 denotes a chain or cord attached to the receptacle 2 and guided by pulleys 14^x and extended to the vicinity of the stool where it

may be provided with a handle or "pull". In some cases a lever 15 can be employed to pull the chain and tilt the water bucket as will be described.

16 denotes a water-supply pipe and 17 a cock or faucet therein, and 18 a pipe from the faucet to a point near the end of the water receptacle as indicated. The faucet has an actuating lever connected to the chain above the bail 3 by means of a slot or loop 20. The faucet is open and closed by means of lever 19 actuated in the following manner. Assuming that the full lines indicate a filled bucket, it will be tilted to empty by a pull at 15 on the chain 14 and will then assume a position approximately indicated by broken lines. This is the position of the bucket when tilted and just before moving up under action of weight 7^x.

21 denotes a stop which may impart a return impulse when struck by the rising corner edge of the emptied bucket moving up from the position indicated in broken lines.

The axis 4 of the bucket is a little to the right of the center of gravity so that a gentle pull on chain 14 will cause the bucket to tilt and empty by gravity. Tilting is stopped by a bucket edge striking the bail chain. As the bucket is emptied it is overbalanced by the weight and rises, its axis 4 moving up in grooves 5. The left lower corner of the bucket will by its ascent under influence of the weight be brought in contact with stop 21, and a return of the bucket from its tilted position begun.

22 denotes the rear end of the receptacle opposite its discharging end, and to which rear end the tilting cord or chain 14 is attached.

21 denotes a stop or projection situated preferably above a horizontal plane passing through the receptacle pivots, and in the path of the rear wall of the receptacle when tilted for discharging whereby a return tilting movement is initiated by reaction of the receptacle against said stop or projection.

23 denotes one or more stops fixed to the inside of the receptacle and in situation to prevent too great a return of the bucket. Its return to normal position is effected by the water discharged through pipe 18. This pipe is extended to near the bottom of the bucket, when it is in position indicated in broken lines, whereby it is quickly submerged by inflowing water and noise stopped.

It will be understood that the weight

raises the bucket as it is being emptied and is itself lowered. When the bucket is filled it is returned to normal position. The packing closes the top of the air chamber between 5 the weight and the bottom of the cylinder 8 but permits air to pass under pressure and thus retards the up and down movements of the weight to provide that the emptying tank shall rise gently and smoothly and be 10 prevented from dropping quickly; and it also provides that these operations shall be noiseless.

Nothing is used in the nature of a valve except the admission cock.

15 It is obvious that lever 6 is not in all cases essential and that a modification such as indicated in Fig. 5 would be operative. In this form pulleys 24, one of which is supported over the bucket substantially as 20 shown, are employed and chain 5^x or its equivalent passed over and connected to the bucket bail.

Other details of construction may be varied without departure from the invention.

25 Having described the invention what I claim is,—

1. The combination of a water receptacle, a suspending device, a water supply pipe, a faucet, a faucet handle, said handle being 30 operatively engaged with said suspending device, and said supply pipe having a downwardly inclined extension opening near the end of the receptacle opposite its outlet end whereby impact of inflowing water tends to 35 return the receptacle to horizontal position, and means for tilting the receptacle.

2. The combination in a flushing device, of a casing; a tilting receptacle; means for tilting the receptacle; a counterbalancing 40 weight, a well to guide the weight, and a partition in the casing inclosing the well, and a stop on the partition, said stop being in the path of the tilting receptacle.

3. The combination in a flushing device, of 45 a casing; a tilting receptacle; a counterbalancing weight, a well to guide the weight, a

partition in the casing and inclosing the well, and a receptacle-moving cord situated adjacent the well and on the same side of the partition.

4. A tilting water receptacle having an inclined discharging end receptacle-supporting pivots, means for tilting the receptacle, and a supply pipe discharging near the end of the receptacle opposite said inclined end whereby impact of inflowing water tends to return the receptacle to horizontal position.

5. In a flushing device, a receptacle, means for tilting it to empty, and a refilling pipe discharging against an end of the receptacle 6 at a point suitable to return said tilted receptacle toward horizontal position by impact of a fresh charge of water.

6. In a flushing device, a tilting water receptacle, means for tilting the receptacle, a 6 stop to limit forward tilting movement of the receptacle, a stop to limit return movement of said receptacle, and a supporting bail for the receptacle, said latter stop being situated within the receptacle and acting on 7 the bail.

7. In a flushing device, a tilting water receptacle; a suspending device therefor, means for tilting the receptacle for emptying it, and two stops, one of said stops consisting of a receptacle-returning device in the path of the rear of the receptacle, and the other of a stop situated within the receptacle and acting on 75 said suspending device.

8. In combination, the water receptacle, 80 a counterbalance support, a water supply pipe, a rotatable faucet in said pipe, a handle directly connecting said faucet and the support, and means to tilt the counterbalanced receptacle.

85 In testimony whereof, I have signed this specification in the presence of two subscribing witnesses:

GEORGE M. DEPEW.
